UNITED STATES PATENT OFFICE.

FRED BRAINARD COREY, OF SPRINGFIELD, MASSACHUSETTS.

STEAM-SEPARATOR.

SPECIFICATION forming part of Letters Patent No. 606,190, dated June 28, 1898.

Application filed April 3, 1897. Serial No. 630,634. (No model.)

To all whom it may concern:

Be it known that I, FRED BRAINARD COREY, a citizen of the United States, residing at Springfield, in the county of Hampden and 5 State of Massachusetts, have invented certain new and useful Improvements in Steam-Separators, of which the following is a specification.

My invention relates to steam-separators— 10 that is, to devices for separating from steam particles of water held in suspension thereby, and thus to deliver steam that is comparatively free from moisture. The same apparatus may evidently be used for removing 15 particles of oil and other liquid or solid impurities from the steam.

The object of my invention is to provide a simple form of such apparatus that shall accomplish its purpose more thoroughly than 20 those now in use by immediately removing the separated water and a small portion of the steam from contact with the main current of rapidly-moving steam, and thus to guard against the possibility of the water being 25 again picked up by the steam and carried on into the main steam-pipe.

My invention consists in the combination, with the main steam-passage and the water-receiver, of a perforated wall separating the 30 said water-receiver from the main steam-passage and a pipe or passage leading from the upper part of the said water-receiver to the said main steam-passage and means whereby a circulation of steam is maintained through 35 the said pipe and through the perforations of the said wall.

In the accompanying drawing, which illustrates my invention, is shown a sectional view of a separator embodying my improvements. 40 It is to be understood, however, that I do not limit myself to this precise construction, as various modifications of this design might be made which would evidently come within the scope of this invention.

In the drawing, A B C D represent the 45 main portion of the separator, which is preferably made of cast-iron in a single piece. This piece is flanged, as shown at A and at D, for attachment to the main steam-pipes. In 50 the lower portion of the said piece A B C D the wall of the casting is perforated by the holes or slots C'. These holes or slots C' are

preferably so placed that one side of each hole or slot is tangent to the curve of the inner surface at C, and thus practically tangent 55 to the path of the steam as it is deflected around this curve in its passage from B to D.

E is a piece of pipe fitted into the casting A B C D, as shown. F is a cone that covers the top of the said pipe E, but is not in direct 60 contact therewith. This cone F may be attached either to the said pipe E or to the walls of the main passage A B in any suitable manner. Thin strips of metal may be connected to the lower edge of the cone F, reaching to 65 the pipe E and attached to the said pipe E at a point below the upper extremity of the said pipe E, as is indicated at M in the drawing; but I do not confine myself to this method of attachment. Thus the said cone F does not 70 obstruct the passage of steam through the said pipe E. The water-receiver or well G is attached to the main casting A B C D by means of the flanges H and the bolts J. This water-receiver G is tapped at the bottom K for the 75 attachment of the drip or waste pipe.

L represents a water-column or gage-glass for indicating the amount of water in the receiver G.

The operation of my invention is as follows: 80 The steam, carrying with it particles of water, enters the separator at A and turns downward through the vertical passage B. As the steam rushes from the end of this vertical passage B the said steam is deflected by the curvature 85 of the perforated wall at C, and thus because of its greater specific gravity the particles of water are thrown downward and outward against the said perforated wall C. The dry steam passes upward and out of the separator 90 at D. Because of the velocity of the steam and particles of water at C a portion of the separated water would be driven through the perforations at C' into the receiver G; but at the same time the rapidly-moving steam 95 would have a tendency to carry the water forward and finally to pick it up again. In order to insure the delivery of dry steam, it is therefore essential that the separated water, together with the layer of steam in contact 100 therewith, be immediately removed from contact with the main current of steam. This I accomplish in the following manner: As the steam in the passage B passes the cone F the

steam in the interior of the said cone F will be withdrawn, thus forming a partial vacuum in the interior of the said cone F. The diminution of pressure at this point causes steam 5 to rise in the pipe E, only to be drawn into the passage B. As steam is drawn upward through the pipe E there is a reduction of pressure within the receiver G, which in turn causes steam to be blown through the perforations C', as desired, thus effectually eliminating the moisture from the steam.

Having described the operations of and the results secured by my invention, I declare that what I claim is—

- 15 1. In a steam-separator, the combination of a main steam-passage, a water-receiver, a perforated wall between the said main steam-passage and the said receiver and an auxiliary steam-passage extending from the upper part 20 of the said receiver to the said main steam-passage, substantially as described.
2. In a steam-separator, the combination of a main steam-passage, a water-receiver, a perforated wall between the said main steam-passage and the said receiver, an auxiliary steam passage or pipe extending from the up- 25

per part of the said receiver to the said main steam-passage and a hollow cone overlapping the end of the said auxiliary steam passage or pipe but not in contact therewith, as set 30 forth.

3. In a steam-separator, an inlet-pipe, a deflecting-plate in close proximity to the end of the said inlet-pipe and perforations in the said deflecting-plate, the said perforations being tangent to the inner surface of the said deflecting-plate, substantially as set forth. 35

4. In a steam-separator, a steam-circulating device consisting of a steam pipe or passage and a hollow cone overlapping the outlet of 40 the said pipe or passage but not in contact therewith, the said pipe or passage being in communication with the water-receiver of the separator, substantially as described.

In testimony whereof I have signed my 45 name to this specification, in the presence of two subscribing witnesses, this 1st day of April, A. D. 1897.

FRED BRAINARD COREY.
